DESIGN FOR A FRAME FOR A HANDBAG

Charles William Hardy, New York, N. Y.

Application June 5, 1945, Serial No. 119,906

Term of patent 14 years

(Cl. D87—2)

To all whom it may concern:

Be it known that I, Charles William Hardy, a citizen of the United States, residing in New York city, in the county of New York and State of New York, have invented a new, original, and ornamental Design for a Frame for a Handbag, of which the following is a specification, reference being had to the accompanying drawing, forming part thereof.

Fig. 1 is a front perspective view of a frame for a handbag showing my design,

Fig. 2 is a similar view of the reverse side thereof,

Fig. 3 is an edge view thereof, and

Fig. 4 is a top open view thereof.

I claim:

The ornamental design for a frame for a handbag, substantially as shown.

CHARLES WILLIAM HARDY.
